CLAIM

The ornamental design for a golf putter head, as shown and described.

DESCRIPTION

FIG. 1 is a top rear perspective view of a golf putter head showing my new design;

FIG. 2 is a rear elevational view thereof;

FIG. 3 is a front elevational view thereof;

FIG. 4 is a side elevational view taken from the right of FIG. 1;

FIG. 5 is a side elevational view from the left of FIG. 1;

FIG. 6 is a bottom plan view thereof;

FIG. 7 is a top plan view thereof;

FIG. 8 is a top plan view of a second embodiment thereof;

FIG. 9 is a top plan view of a third embodiment thereof;

FIG. 10 is a top plan view of a fourth embodiment thereof;

FIG. 11 is a top plan view of a fifth embodiment thereof; and,

FIG. 12 is a top plan view of a sixth embodiment thereof.

The remaining views of the second through the sixth embodiment are the same as in FIGS. through 6.
